COOLING UNIT

Harold A. Greenwald, Detroit, Mich., assignor, by
mesne assignments, to Kelvinator Corporation,
Detroit, Mich., a corporation of Michigan

Application May 18, 1931, Serial No. 538,335

6 Claims. (Cl. 62—95)

This invention relates generally to cooling units for refrigerating apparatus and consists of certain novel features of construction, combinations and arrangements of parts that will be herein-
5 after more fully described and particularly pointed out in the appended claims.

Heretofore in the construction of cooling units metal such as aluminum has been cast about copper tubing to form the body of the cooling
10 unit. However, it has been found that the combination of aluminum and copper is objectionable. For example, the tendency of one metal to have electrolytic action with another as a general rule depends upon how far apart they
15 are in the electromotive series. The farther apart they are the more rapid is the electrolytic action. Moreover, metals are chemically active and corrode in the order of their position in the electromotive series. Aluminum and copper are
20 quite far apart in the electromotive series, consequently when aluminum is cast upon copper tubing to form a cooling unit which is subject to moisture conditions electrolytic action is set up and corrosion will take place.
25 In the present instance I employ steel tubing in aluminum and the latter is so shaped that cores are eliminated. Moreover, in the construction of cooling units, I have found that it is better to have steel or iron cast in the aluminum
30 because the aluminum and steel are closer together than aluminum and copper in the electromotive series and the chemical action between such metals is slower when subjected to moisture. In addition the steel is preferable as the
35 cost thereof is less than that of the copper.

In the accompanying drawings:

Figure 1 is a front elevation of a cooling unit embodying my invention;

Figure 2 is a side elevation of the unit;

Figure 3 is a bottom plan view of one section of the unit;

Figure 4 is a horizontal sectional view through one section of the unit;

Figure 5 is a front elevation of a slightly modified construction.

Referring now to the drawings, A is a cast metal body, and B and C respectively are refrigerant expansion coils of a cooling unit embodying my invention. As shown, the body A is substantially square shape in cross section and comprises two complementary sections 1 and 2 respectively that are bolted together at the top and bottom thereof. In the present instance the sections 1 and 2 are castings and are preferably formed of aluminum or commercial alu-

minum alloy. Substantially parallel fins 3 extend longitudinally of and project radially from the top, side and bottom walls 4, 5 and 6 respectively of each section while substantially horizontal ribs 7 project inwardly from the side walls 5 of the sections and constitute shelves for supporting ice trays and the like. The coils B and C are preferably formed of steel tubing and are embedded in the side walls 5 of the aluminum body. Preferably the coils have substantially straight portions 8 projecting through the rear walls 9 of the sections and connected by a short length 10 of tubing, and have other straight portions 11 that terminate immediately in rear of threaded openings 12 in the side walls 5 of the sections. An expansion valve 12' is adapted to be secured in one threaded opening 12 while an elbow 12'' is adapted to be secured in the other opening 12 and is connected to the return line 14 to the compressor. In use the unit may be 10 mounted in the refrigerating chamber of a cabinet so that the aluminum body may absorb the heat within the cabinet and transmit it to the steel tubing of the coils where it is carried by the refrigerant therein back to the compressor 15 of the apparatus. Consequently the maximum efficiency is obtained.

In Figure 5 I have illustrated a slight modification wherein the sections 15 and 16 of the cooling unit are entirely devoid of ribs such as 7 and 30 are bolted together so that the joint between the two is in a horizontal plane. With this construction a plate 17 is clamped between the opposed edges of the sections and constitutes a shelf for supporting an ice tray or the like.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

1. A cooling unit having a body formed of complementary sections, each section having a threaded opening, and refrigerant expansion coils embedded in said sections, one in each section, one end of each coil being adjacent and communicating with a threaded opening, and the other end of each coil projecting through a wall 50 of the section, and a separable connecting member between the last mentioned projecting end portions of said coils, said connecting member being so constructed and arranged as to both join the coils and clamp the sections together.

2. A cooling unit having a body portion comprising two similar sections secured together to provide top, bottom and side walls of a freezing zone, a spiral refrigerant coil embedded in said side wall formed by one of said sections, a spiral refrigerant coil embedded in the side wall formed by the other section, said coils extending over relatively large portions of said side walls, and an independent connection between said coils.
- 10 3. A cooling unit having a body portion comprising two similar sections secured together to provide top, bottom and side walls of a freezing zone, means secured to said sections to provide a rear wall of said freezing zone, coiled refrigerant conduits embedded in walls formed by said sections and having substantially straight portions extending through said means, and a connection between said portions for circulating refrigerant from one conduit to another.
- 15 4. A cooling unit having a body portion comprising complementary sections secured together to provide walls of a freezing zone, a member secured to said sections to provide a rear wall of said zone, coiled refrigerant conduits embedded in walls formed by said sections and having substantially straight portions extending from said walls through said member, and a connection between said portions for circulating refrigerant from one conduit to another.
- 20 5. A cooling unit having a body portion comprising complementary sections to provide walls of a freezing zone, a member secured to said sections to provide an additional wall of said freezing zone, coiled refrigerant conduits embedded in walls formed by said sections and having end portions extending through said member, and a connection between said portions for circulating refrigerant from one conduit to another.
6. A cooling unit having a body comprising two complementary C-shaped sections secured together adjacent the top and bottom to provide a freezing zone, a refrigerant evaporating coil embedded in a side wall of said zone formed by one of said sections, a refrigerant evaporating coil embedded in the opposite side wall of said zone formed by the other section, and an independent connection between said coils.

HAROLD A. GREENWALD.
